FIGURE 1 is a perspective view of the combined multi-television receiver unit and support stand therefor showing my new design;

FIG. 2 is a top plan view showing the top of the housing;

FIG. 3 is a front view of the housing; and

FIG. 4 is a side elevational view of the housing.

The back of the unit is conventionally plain, flat and unornamented. The dominant features of my design reside in the portions shown in full lines on the drawings.

I claim:

The ornamental design for a combined multi-television receiver unit and support stand therefor, as shown and described.
